UNITED STATES PATENT OFFICE.

CARL WALther, OF CHEMNITZ, GERMANY, ASSIGNOR TO THE FIRM OF SCHUBERT & SALZER MASCHINENFABRIK AKTIENGESELLSCHAFT, OF CHEMNITZ, GERMANY.

THREAD-TIGHTENER OF WARP-LOOMS.

1,318,625.

Specification of Letters Patent.

Patented Oct. 14, 1919.

Application filed October 26, 1916. Serial No. 127,742.

To all whom it may concern:

Be it known that I, CARL WALther, a citizen of Germany, and residing at Chemnitz, in the German Empire, have invented 5 new and useful Improvements in Thread-Tighteners of Warp-Looms, of which the following is a specification.

This invention relates to devices in warp looms for imparting the proper tension to 10 the warp threads and is especially designed for warp looms in which a separate warp is supplied to the front series of guide needles as well as to the rear series of guide needles.

15 Hitherto, both of these warps were wound upon separate warp beams and from these separately mounted warp beams the warp threads were fed to the respective guide needles over separate thread tighteners. 20 Both tighteners had to be very accurately adjusted in order to insure an entirely uniform thread feeding of the warps, which is a requisite for the production of a really good fabric. Not only does any variation 25 in the tension of the threads render the fabric streaky, but considerable losses of thread material accrue owing to the fact that of the two warps which originally were of equal length, one warp is sooner worked 30 up than the other, and the remainder of the latter cannot be used further but has to be thrown away as waste.

Efforts have been made to get rid of this 35 drawback by warping both threads upon a single beam and feeding the threads to the needles over separate tighteners. With this arrangement it still remains a difficult thing to adjust both tighteners to conform so that the same will produce an equal feed of, and 40 a uniform tension in, the thread.

The drawback of an unequal consumption 45 of warp threads can be overcome by the application of a single warp beam. However, then there is a still greater necessity of obtaining an equal tension on the threads. If variations occur in the tension 50 of the threads, and the tension of one thread system preponderates, this part of the warp would be drawn off and the other part would naturally be taken along with the tensioned part; it is to be anticipated that the threads of this latter part will lie too loosely in the fabric produced.

Hence, it is difficult to produce a satis-

factory uniform fabric by the means and 55 expedients hitherto proposed.

It is the object of my present invention to provide means which will enable the removal of all of these drawbacks. This object I attain by placing both warps upon a 60 single warp beam and mounting both thread tighteners upon a common tightening lever; thereby, any variation in the tension of the threads is equally distributed upon both warps.

65 The figure shows an embodiment of my present invention by way of example.

In the embodiment of my present invention, as illustrated diagrammatically in the drawings, the warps 4 and 5 which are to 70 supply the threads for the needles on the thread bars 8 and 11 respectively, are wound upon a common warp beam 2 supported in bearings of the machine frame 1 in a manner well known. A depending lever 12 is fulcrumed on the machine frame and provided with two arms 13 and 14 which carry at their ends transversely disposed thread tightening rods 15 and 16 respectively. The threads of the warp 4 are passed over the 75 thread tightener 15 while the threads of the warp 5 pass over the thread tightener 16. The said lever is subject to the action of a single helical spring 6, which is hooked with one end to the extreme of the arm 13, 80 and which is connected with its opposite end to an adjustable screw member 26 shown to be mounted in the machine frame 1. The tightening effect of the lever 12 upon the threads of the two warps 4 and 5 can be 85 accurately regulated by means of the said member 26 controlling the spring 6; and any adjustment is equally transmitted to both warps.

90 Since the threads of the two warps are led to the two thread bars from different directions, the thread tightening rods 15 and 16 must be disposed so that a uniform feed with threads having equal tensions can be obtained. The threads of the warp 4, in 95 passing over the tensioning rod 15, form an angle *a* which is larger than the angle *b* formed by the warp threads passing over the tensioning rod 16. Now, it becomes obvious from the drawing that the larger the 100 angle is which the thread forms, the shorter is the path of contact between the thread and the tensioning rod over which the thread 105

passes, and vice versa, because the threads of both warps are supplied from one and the same level while the tensioning devices are necessarily disposed on different levels. 5 Since the amount of friction producing the tensioning effect upon the threads is proportional to the length of the path of contact between the threads and the respective tensioning rod, provision must be made for 10 the compensation of the difference existing between the two tighteners 15 and 16 in this respect. The required compensation I obtain by giving the arms 13 and 14 supporting the tensioning rods 15 and 16 at their 15 respective ends, a different leverage.

The lever length of the arm 13 supporting the tensioning rod 15 exceeds the lever length of the arm 14 for the tensioning rod 16. Both of the said tensioning rods, however, swing with a common lever 12, hence, both must necessarily participate in the same movement. The leverage of the longer arm carrying the tightening rod that affords the smaller frictional contact with the threads 25 is larger than the leverage of the shorter arm 14 carrying the tightening rod having the larger frictional contact with the threads. In this manner, the difference in the drawing force exerted upon the two threads is 30 compensated for, which difference is caused by the difference in the angular guide way for the threads. The smaller friction produced within the larger angle a and multiplied by the larger leverage yields the same 35 momentum as the larger friction that is produced within the smaller angle b and multiplied by the smaller leverage.

Any variation in the tension is equally distributed upon both tightening rods 40 through the spring 6 common to both. The possibility of any difference of tension in the threads is effectually removed through my invention.

The scope and utility of my invention is 45 not restricted to the particular form of the device I have illustrated in the drawings; modifications may be made in various respects without thereby involving any departure from the essence of my invention 50 which I have set forth hereinbefore.

What I claim as my invention and desire to secure by Letters Patent of the United States, is:—

1. In a warp loom, the combination of a single warp beam adapted to supply two warps simultaneously, two guide needle bars and guide needles thereon; with a single oscillatory mounted member, an extension on said member, a thread tightener on said extension, a second extension on said member, a thread tightener on said second extension, said latter thread tightener having a leverage different from the leverage of the first-named thread tightener, and an adjustable spring connected to said member to exert a thread tightening action upon the thread tighteners on said member, whereby the thread-tightening action of said tighteners may be simultaneously regulated. 65

2. In a warp loom, the combination of a single warp beam adapted to supply two warps simultaneously, two guide needle bars and guide needles thereon; with a single oscillatory mounted member, an arm on said member, a thread tightener on said arm, a second arm on said member and extending in another direction than said first named arm, a thread tightener on said second arm, said latter thread tightener having a leverage different from the leverage 75 of said first named thread tightener, and an adjustable spring connected to said member so as to exert a thread tightening action upon said thread tighteners on said member, whereby the tightening action of said thread 80 tighteners may be regulated.

3. In a warp loom, the combination of a single warp beam adapted to supply a pair of warps, a pair of guide needle bars and guide needles thereon; with a single oscillatory mounted member pivotally mounted at one end, a pair of thread tighteners on said member at different distances from said end, the said thread tighteners being so located 90 on said member as to have different leverages, and a spring adapted to act upon said member.

In testimony whereof I have hereunto affixed my signature.

CARL WALTHER.
